UNITED STATES PATENT OFFICE

ROY L. BURCH, OF MONTROSE, COLORADO

GATE

Application filed December 27, 1928. Serial No. 328,806.

This invention relates to gates and particularly to the means whereby the gates may be opened and closed by a person approaching the gate either walking or in a vehicle and whereby the gate may be closed after the person or vehicle has passed the gate.

The general object of the invention is to provide a very simple, easily operated mechanism for this purpose so constructed that upon strain being applied to a cable at a distance from the gate, the gate will be tilted slightly upward at its forward end to thereby unbalance the gate and cause it to swing automatically from a closed to an open position and when strain upon the cable has been relaxed, permit it to return to its balanced position, the mechanism being such that after the party has passed the gate, a pull upon the cable will again raise the free end of the gate to thereby unbalance it and cause it to swing under a slight impulse to a closed position, a latch operating to latch the gate in its closed position as soon as it is in alignment with the gate post.

A further object is to provide means whereby the extent to which the gate may be raised at its front end may be regulated.

Other objects will appear in the course of the following description.

My invention is illustrated in the accompanying drawings, wherein:

Figure 1 is a perspective view of a gate operating mechanism constructed in accordance with my invention;

Figure 2 is a top plan view of the operating mechanism;

Figure 3 is a side elevation thereof partly in section;

Figure 4 is a like view to Figure 2 showing the position of the parts when the gate operating mechanism is swung by one of the cables;

Figure 5 is a fragmentary top plan view of the arm 18 and the butt thereof;

Figure 6 is a fragmentary vertical section through the latching post, the keeper and the gate with the latch.

Referring to these drawings 10 designates the gate post upon which the gate designated generally 11 is swung. Opposed to the gate

post 10 is a gate post 12 having thereon the latch keeper 13 which is of ordinary form and vertically cleft at its middle to receive a latch bolt 14 mounted upon the gate. This latch bolt is urged to a projected position by a spring 15 and is prevented from being projected too far by means of a stop 16.

The gate at its rear lower corner is hinged by means of the usual hinge pintle 17 engaging an eye or eye bolt 17^a projecting from the gate post 10. So far I have described what is practically an ordinary gate except as regards the particular form of latch bolt.

For the purpose of permitting the release of the gate by a person a distance from the gate, I mount upon the top of the post 10, the rearwardly extending arm 18 which at its rear end is provided with a pulley 19 and below the pulley with a downwardly bowed prong engaging a guard 20. This member 18 is rigidly mounted upon the top of the post but projects inward beyond the post and is provided with the annular hub 21. Disposed above the member 18 and normally in alignment therewith is a gate operating arm 22 preferably T-shaped in cross section for a portion of its length as is the arm 18, this arm 22 at its outer end being downwardly beveled and formed with the cable engaging eye 23. The butt end of the arm 22 is laterally extended to form the ears 24 which are apertured and forward of these ears and projecting downward from the under face of the arm 22 is a pin 25 which engages in the opening in the hub 21. Projecting upward from the upper face of the butt end of the arm 22 but rearward of the pin 25 is a pin 26. Mounted upon the upper face of the gate at the butt end thereof is a strap 27 which is apertured at 28 for the passage of screws, bolts or other attaching devices whereby it may be held upon the upper edge of the gate.

The rear end of the member 27 projects beyond the gate and this rear end is provided with the longitudinally extending slot 29 which is defined upon the upper face of the member 27 by the upwardly extending guides 30. The inner end of the slot on the under face of the strap is defined by a transversely extending stop 31. Slidingly mounted be-

tween the guides is a slide 32 held in place by the bolt 33. This slide 32 constitutes an adjustable stop as will be later seen.

Projecting laterally from the strap 27 are 5 lugs 34 disposed in a horizontal plane and apertured each for the passage of a link 35. The outer end of each link is screw-threaded and receives a nut 36, while the inner end of each link is angularly bent at 37, these angular 10 ends engaging in the perforated ears 24 of the arm 22.

Mounted upon posts 38 and 39 are pulleys 40 and passing over these pulleys is a cable 41, the middle of this cable being attached to 15 the eye 23 on the outer end of the arm 22 and the cable being adapted to pass over the pulley 19 and prevented from operative disengagement from this pulley by the guard 20. The outer ends of the cable are provided 20 with handles 42 whereby the cable may be pulled in either direction.

The operation of this device is as follows:—

Assuming that the gate is closed and the latch bolt 16 is engaged with the keeper 13, 25 then as a person approaches the gate, as for instance in a vehicle, and desires to open the gate without dismounting, the person pulls upon one of the handles 42. This retracts the cable. The first result of this pull is to 30 turn the arm 22 upon the axis of the pin 25 so that the pin 26 acts as a crank moving away from the gate. When this crank has been turned sufficiently, one of the lugs 24 will exert a pulling action upon one of the links 35, the other link sliding through the opening in the corresponding lug 24 and this will act to tilt the gate upward, this rearward motion of the top of the gate being permitted by the slot 29. When the gate has been pulled 40 open a sufficient extent, it will be overbalanced and will naturally tend to swing open, the direction of the swing being controlled by a slight pull on the arm 27.

In other words, the first pull upon the 45 cable acts to release the gate from the keeper 13 not by retracting the latch but by lifting the forward end of the gate and the latch out of engagement with the keeper 13. A slight further pull upon the cable will cause the 50 unbalanced gate to swing to an open position. As soon as the cable is released and by the time the gate has arrived at the open position, it will once more be horizontal and will, therefore, stay in the position to which it 55 has been opened. After the traveller has passed through, the handle on the other side is pulled. This will again act to lift the forward end of the gate so as to render it unbalanced and at the same time the stop 36 60 contacts with the lug 34 and the gate is given an impulse which with the unbalancing of the gate will swing it to a closed position. Just before the gate has reached its closed position, it is returned to horizontal position and 65 the latch bolt 14 is forced rearward against

the action of the spring 16 and then the bolt is projected into the keeper as soon as it reaches the cleft thereof.

It will be seen, therefore, that I have provided a very simple and effective means whereby the gate may be opened and closed, which means depends for its action upon the fact that the arm 22 constitutes practically a crank arm which, as the arm is swung acts to lift up on the forward end of the gate and which then, when the nut 36 engages the ear 34, acts to swing the gate. When strain upon the cable is released, the gate will still continue to swing due to its momentum but will sink back to its horizontal position.

By adjusting the slide 32, the amount that the forward end of the gate may be raised is controlled. By adjusting the nuts 36, the amount of movement necessary before the gate is raised is controlled. With this device, the gate is rendered unbalanced and swings to its open position upon a slight pull of the controlling cable and is again rendered unbalanced and at the same time is given a slight impulse to move to its closed position when the cable is pulled in the opposite direction.

While I have illustrated certain details of construction and arrangement of parts, I do not wish to be limited thereto as it is obvious that many changes might be made without departing from the spirit of the invention as defined in the appended claims.

It will be obvious that the same kind of a latch 14 may be used in connection with the posts 38 and 39 as is used on the posts 12 to thus hold the gate open.

I claim:—

1. In a gate structure, a gate post, a gate hingedly connected to the post adjacent its lower corner, a strap mounted upon the upper edge face of the gate at its upper corner and extending toward the post and longitudinally slotted, an arm operatively pivoted upon the post, the arm rearward of said pivotal point having an upwardly projecting pin extending into said slot, said arm at its rear end being provided with laterally projecting ears, the strap having eyes, links slidingly engaging said eyes and engaging in said ears, the links having stops on their ends disposed to engage the eyes, a normally projected spring latch mounted upon the free end of the gate and a keeper with which the latch engages and from which the latch is freed upon the lifting of the forward end of the gate, and a cable attached to the extremity of said arm and extending in opposite directions therefrom and whereby the arm may be swung in one direction or the other.

2. In a gate structure, a gate post, a gate hingedly mounted adjacent its lower corner upon said gate post, an arm rigidly mounted upon the upper end of the gate post, the outer end of the arm being provided

with a pulley and a downwardly bowed guard, a second arm pivotally mounted upon the butt end of the first named arm for swinging movement and rearward of said pivotal axis having an upwardly extending pin, the second arm at its rear end being provided with laterally projecting ears, a strap mounted upon the upper edge face of the gate and extending beyond the same and having a longitudinally extending slot through which said pin on the second named arm passes, said strap having laterally projecting eyes, links engaging the ears on the second arm and having limited sliding engagement through the eyes on said strap, and a cable attached to the rear end of the gate operating arm and extending in opposite directions and adapted to engage said pulley, the strain upon the cable in one direction or the other acting to shift the gate operating arm to thereby lift the forward end of the gate to release it from the latch to permit it to swing.

3. In a gate structure, a gate post, a gate hingedly mounted adjacent its lower corner upon said gate post, an arm rigidly mounted upon the upper end of the gate post, the outer end of the arm being provided with a pulley and a downwardly bowed guard, a second arm pivotally mounted upon the butt end of the first named arm for swinging movement and rearward of said pivotal axis having an upwardly extending pin, the second arm at its rear end being provided with laterally projecting ears, a strap mounted upon the upper edge face of the gate and extending beyond the same and having a longitudinally extending slot through which said pin on the second named arm passes, said strap having laterally projecting ears, links engaging the ears on the second arm and having adjustable stops engageable with the perforated eyes on the strap and having limited sliding engagement through the eyes on said strap, and a cable attached to the rear end of the gate operating arm and extending in opposite directions and adapted to engage said pulley, the strain upon the cable in one direction or the other acting to shift the gate operating arm to thereby lift the forward end of the gate to release it from the latch to permit it to swing.

4. In a gate structure, a gate post, a gate hingedly mounted adjacent its lower corner upon said gate post, an arm rigidly mounted upon the upper end of the gate post, the outer end of the arm being provided with a pulley and a downwardly bowed guard, a second arm pivotally mounted upon the butt end of the first named arm for swinging movement and rearward of said pivotal axis having an upwardly extending pin, the second arm at its rear end being provided with laterally projecting ears, a strap mounted upon the upper edge face of the gate and extending beyond the same and having a longitudinally extending slot through which said pin on the second named arm passes, said strap having laterally projecting eyes, links engaging the ears on the second arm and having limited sliding engagement through the eyes on said strap, and a cable attached to the rear end of the gate operating arm and extending in opposite directions and adapted to engage said pulley, the strain upon the cable in one direction or the other acting to shift the gate operating arm to thereby lift the forward end of the gate to release it from the latch to permit it to swing.

5. In a gate structure, a post supporting the gate, the gate having swinging engagement at its lower rear corner with said post, a latch on the gate, a keeper with which the latch is adapted to be engaged, the keeper opening upwardly whereby as the free end of the gate is raised, the latch will be released from the keeper, an arm mounted for coaction with the gate and upon the gate post, a cable engaging said arm and extending in opposite directions therefrom and provided with means whereby strain may be applied to either end of the cable to rotate said arm, the arm having a pivot pin disposed forward of the axis of the arm and having sliding engagement with the gate, the arm acting when rotated by the cable to lift the forward end of the gate to thereby unbalance the gate and permit it to swing to an open position or to swing from an open position to a closed position.

6. In a gate structure, a post, a gate hinged to the post adjacent its lower corner, an arm pivotally mounted upon the post and having laterally projecting ears, eye members carried by and projecting laterally from the gate adjacent its upper rear corner, and links connected to said ears and having limited sliding movement through said eyes, and a cable operatively engaged with said arm whereby the gate may be swung to an open or closed position.

In testimony whereof I hereunto affix my signature.

ROY L. BURCH.
